UNITED STATES PATENT OFFICE.

LUTHER C. BALDWIN, OF MANCHESTER, NEW HAMPSHIRE.

APPARATUS FOR DRYING BOBBINS.

SPECIFICATION forming part of Letters Patent No. 237,074, dated January 25, 1881.

Application filed June 21, 1880. (No model.)

To all whom it may concern:

Be it known that I, LUTHER C. BALDWIN, of Manchester, Hillsborough county, New Hampshire, have invented a new and Improved 5 Apparatus for Drying Bobbins, of which the following is a specification.

In the manufacture of wooden bobbins it is required that the end of each be painted, and it is usual to use a quick-drying paint and lay 10 the bobbins aside on boards to dry, arranged so that the ends shall not touch.

The object of my invention is to dispense with these boards and save the time required for handling them and the bobbins; and my 15 invention consists of a flexible endless belt fitted with slats having concave sides adapted for receiving and carrying the bobbins. The belt is arranged to run around the friction-rolls slowly to the distance required, and the 20 bobbins will be placed in at one end of the apparatus and discharged at the other end. Combined with the belt is a device for registering the discharge of each bobbin and keeping 25 a record of the number.

25 In the accompanying drawings, which show an apparatus embodying my invention, Figure 1 is a sectional side elevation, and Fig. 2 is a face view, of a portion of the belt.

Similar letters of reference indicate corresponding parts.

30 A is the belt, which is made of flexible material and supported on the rollers a a' a' , to one of which power will be applied in any desired manner to give a slow continuous movement of the belt around the rollers. The rollers a a' are sustained in suitable supports, b , which may be upon a suitable frame; or the 35 lower supports may be upon the floor of a building and upper supports depend from the ceiling; or, in case it is not desired to occupy 40 the floor room, the belt may return over rollers, also suspended from the ceiling, as shown in dotted lines.

Upon the belt A are secured the lags or 45 blocks c , which may be made of wood or other suitable material, and secured by pins or screws, or other desired means, whereby they will be held securely. These lags c are concaved or recessed upon their sides in the direction of the width of the belt, and are placed slightly apart, so that the intervening spaces are of a size for receiving the bobbins snugly, as shown in Fig. 2. At the turn of the belt around the rollers the space between the lags 50 c will necessarily widen, so that the bobbins

may be put in at the roller a' on the ascending portion of the belt, and will drop out at the roller a' on the descending portion. Beneath the delivery end is fixed an inclined board, d , for receiving the bobbins as they fall from the belt, and for directing them into a suitable receptacle.

Above the delivery-board d , and at the outside of the belt A, a cross-shaft, l , is fitted in suitable bearings, which shaft will be connected 65 with registering mechanism of any desired character. Upon this shaft there are fixed arms f , four (more or less) in number, so that there shall be one of said arms extending in the path of the ends of the bobbins that project from the side of the belt. The shaft l will thereby be given a quarter-turn by each bobbin brought down by the belt, and a register thus kept of the number discharged.

The bobbins, as they are painted, are placed 75 in the belt, and are carried to the delivery-roller. They thus have time to dry, and are collected in the receptacle without further handling or attention.

The apparatus may be used for drying other 80 articles than bobbins.

I have shown a board, g , hung on the shaft e , in front of the belt, for guiding the bobbins as they pass between the belt and registering-shaft. This board may be used, if required.

The apparatus may be used to dry any articles for which it is adapted.

Having thus described my invention, I claim as new and desire to secure by Letters Patent—

1. The drying apparatus for bobbins, &c., consisting of a traveling endless belt provided with lags c , adapted for sustaining the bobbins, substantially as shown and described. 95

2. In drying apparatus for bobbins, &c., the endless belt A, provided with lags or blocks c , the supporting-rollers a a' , one of which is fitted for connection to power, and the delivery-board d , combined for operation, substantially as shown and described. 100

3. In combination with the traveling-belt A, provided with the bobbin-carriers c , the shaft l , provided with the radial arms f , and connected with suitable registering mechanism, substantially as and for the purpose set forth. 105
